BULLET PROTECTION GUARD

George P. Wiedman, North Tonawanda, N. Y.

Application May 21, 1943, Serial No. 487,897

2 Claims. (Cl. 109—49.5)

This invention relates to a bullet protecting screen and more particularly to such a screen which can be used in protecting the pilots of airplanes or the operators of tanks or other military equipment and at the same time provide the necessary visibility.

One of the principal objects of the invention is to provide such a protective screen which will protect the operator of such military equipment from bullets of the large caliber now used in aerial and tank warfare and at the same time provide a large open space through which the operator of the equipment has a clear view of the surrounding space so that he can operate the equipment at full efficiency and is aware of the conditions which he is called upon to meet.

Another object of the invention is to provide such a screen which is comparatively light in weight, considering the function which it performs, thereby enabling it to be used in airplanes.

Another object of the invention is to provide such a screen which is always in an operative condition and does not require the user to adjust anything in order to obtain a view of the surrounding space.

Another object is to provide such a screen which is composed of two protecting mediums, the first deflecting or reducing the velocity of a bullet to a point where it cannot penetrate the second.

In the accompanying drawing:

Fig. 1 is a fragmentary front elevation of a bullet protecting screen embodying my invention.

Fig. 2 is a horizontal section, taken on line 2—2, Fig. 1.

The guard or screen embodying my invention is shown as mounted in front of an opening 5 in the fuselage or body 6 of an airplane, tank or other military vehicle, although it will be understood that the invention can be used wherever it is desirable to provide protection of this character. The opening 5 is shown as having a frame 7 which can be of any suitable character to support a pane 8 of so-called bullet-proof glass which can be composed of laminated panes of glass and cellulose or otherwise formed as now known in the art. Such glass has comparatively high resistance to the impact of small bullets but does not protect the person behind the opening 5 from bullets of the large caliber and high velocity now used in aerial and tank warfare. To protect the operator of the tank or airplane from such high velocity large caliber bullets, I provide a screen in front of the opening 5 which is shown as comprising a top rail

10 secured to the exterior of the body 6 above the opening 5, a bottom rail 11 secured to the exterior of the body 6 below the opening 5 and two series of vertical bars 12 and 13 carried by these rails. These rails can be rotatably secured to the body in any suitable manner and are shown as having a plurality of circular recesses 15 in their opposing sides which lead to smaller coaxial bores 16 extending through the rails. The bars 12 and 13 are preferably of identical form, each comprising a cylindrical body, the end of which fits into a corresponding recess 15 and end pins 18 which fit into the corresponding bores 16 of the two rails. By mounting the bars so as to be rotatable, the tendency for the bars to be bent on impact is reduced.

The bars 12 and 13 can be made of a metal which has sufficient strength to resist the impact of large caliber high velocity bullets.

20 An important feature of the invention resides in the spacial relationship of the bars 12 and 13. As best shown in Fig. 2, these bars are provided in two series, the outer series being designated at 12 and the inner series being designated at 13 and the bars of the two series being in uniform staggered relation to one another. It will further be seen that the diameter of each bar is less than the width of the free space between any two of the bars of one series and that the bars of each series are spaced the same distance from one another. It will further be noted that the bars of the outer series are arranged within the plane of the outer extremities of the bars of the inner series, although it will 30 be understood that the invention is not necessarily limited to a flat screen but could be provided in a curving screen, the use of the word plane in the accompanying drawings being intended to include such curvature.

40 By arranging the two series of bars 12 and 13 in the manner shown it will be seen that the operator, whose point of vision is indicated at A, has a view of the surrounding outside between the bars, as indicated by the ten pairs of diverging dash lines B. It will further be seen that by shifting the point of view a very slight extent to the left or right, as viewed in Fig. 2, the operator can swing the lines or planes of vision B so as to cover the entire surrounding territory, thereby avoiding any blind spots. While the total amount of light coming through the window 8 is, of course, reduced by the presence of the bars 12 and 13, the operator, with very slight movement of his head, is afforded a complete view of the surrounding territory or space

and by actual test this has been found to be adequate.

The bars 12 and 13 are arranged sufficiently close so that large caliber bullets coming from any direction are prevented from passing therebetween. Such bullets are either ricocheted off, or if they succeed in passing through the bars, as by flattening of the bullet or spreading of the bars, their velocity is reduced to such an extent as to be unable to penetrate the glass pane 8. Any bullets of sufficiently small diameter to pass between the bars 12 and 13 do not have sufficient mass to penetrate the glass screen. It will therefore be seen that the present invention provides a high degree of protection against both small and large caliber bullets without at the same time reducing the effective vision of the operator to a point where it would become unsafe. It will further be seen that the invention does not require the operator to adjust anything in order to obtain a view of the countryside, it being merely necessary for him to move his head slightly to obtain a full view of the surrounding space.

I claim as my invention:

1. A transparent bullet protection guard, comprising a screen including two parallel series of

spaced parallel bars, the bars of one series being in staggered relation to the bars of the other series to provide a zigzag series of spaces between the bars of the two series, the width of said spaces being smaller than the bullets against which protection is afforded, and means for holding said bars in position, said spaces permitting the observation, through said guard, of an object placed in any position on the other side of the guard.

2. A bullet protection guard, comprising a screen including two parallel series of uniformly spaced parallel cylindrical bars of a uniform diameter less than the width of the spaces between the bars of either series, the bars of one series being in staggered relation to the bars of the other series to provide a zigzag series of open spaces between the bars of the two series, the bars of the outer series extending through the plane of the outermost extremities of the bars of the inner series and the width of said zigzag spaces being less than the diameter of said bars and smaller than the width of said first spaces and smaller than the bullets against which protection is afforded, and means for holding said bars in position.

GEORGE P. WEEDMAN.
